UNITED STATES PATENT OFFICE.

OLBERT C. NOBLE, OF WASHINGTON, PENNSYLVANIA, ASSIGNOR TO TYGART VALLEY
GLASS COMPANY, OF WASHINGTON, PENNSYLVANIA. A CORPORATION OF WEST VIRGINIA.

DESIGN FOR A GLASS JAR.

Application filed October 15, 1924. Serial No. 11,075. Term of patent 7 years.

To all whom it may concern:

Be it known that I, OLBERT C. NOBLE, a citizen of the United States, residing at Washington, in the county of Washington, State of Pennsylvania, have invented a new, original, and ornamental Design for a Glass Jar, of which the following is a specification, reference being had to the accompanying drawing, forming a part thereof.

The figure is a perspective view of a glass jar embodying my design.

I claim:

The ornamental design for a glass jar as shown.

OLBERT C. NOBLE.
